UNITED STATES PATENT OFFICE.

FREDERICK LINCOLN, OF WARREN, MASSACHUSETTS; ALICE G. LINCOLN
ADMINISTRATRIX OF SAID FREDERICK LINCOLN, DECEASED.

COMPOUND ENGINE.

SPECIFICATION forming part of Letters Patent No. 755,508, dated March 22, 1904.

Application filed February 13, 1902. Serial No. 93,951. (No model.)

To all whom it may concern:

Be it known that I, FREDERICK LINCOLN, a citizen of the United States, residing at Warren, in the county of Worcester and State of 5 Massachusetts, have invented a new and useful Compound Engine, of which the following is a specification.

This invention relates generally to steam-engines, and particularly to compound engines, 10 it being understood that the principle of the invention is applicable to triple-expansion engines and also to expansion-engines of higher multiples.

The object of the invention is to prevent 15 back pressure, common in compound engines as now constructed; and incidental to the removal of the back pressure the invention also has for its object to increase the efficiency of the ordinary vacuum-pump now used in connection with compound expansive engines.

With these objects in view the invention consists in the novel features of construction and combination, all of which will be fully described hereinafter and pointed out in the 20 claims.

In the drawings forming part of this specification, Figure 1 is a side elevation of an engine constructed in accordance with my invention, two sets of cylinders being illustrated, and also the manner of connecting the 25 valves. Fig. 2 is a sectional view taken through one set of cylinders and illustrating the relative position of the various ports and valves during the downstroke of the high-pressure-cylinder piston A', intermediate-cylinder piston B', and upstroke of the low-pressure-cylinder piston C'. Fig. 3 is a similar view illustrating the relative position of the ports and valves during the upstroke of the said 30 high-pressure-cylinder piston, piston B', and upstroke of piston C'.

In constructing an engine of the kind shown in the drawings I employ three cylinders A, B, and C. The cylinders A and B are integral and arranged tandem-like, the cylinder C being preferably arranged at one side of the cylinder B. The cylinder A is a high-pressure cylinder, and the cylinders B and C are respectively low-pressure, secondary, and tertiary.

cylinders. My invention relates especially to the manner of feeding the steam from one of these cylinders to the other. A piston A' works in the cylinder A, and a piston B' in the cylinder B, both pistons being mounted on the piston-rod B². In the cylinder C is a 55 piston C', secured at the inner end of a piston-rod C². The outer ends of both these piston-rods are secured to suitable crank-rods arranged at an angle of one hundred and eighty degrees to each other. 60

Before describing the construction of the valve passages and ports in detail it may be first stated that I employ the Corliss valve, though slide-valves could be used, and that any desired mechanism may be used for actuating 65 these valves, and any suitable governor may be used with the engine, the valve-actuating mechanism not being a part of this invention.

Fresh live steam is admitted into the cylinder A only, and for this purpose the port 70 A² is provided on one side and midway the ends of the cylinder. This inlet A² has direct communication only with the valve-casing A³, which in turn communicates with the valve-casing A⁴ through a grated valve-seat A⁵, and 75 the casing A⁴ has communication with the cylinder A through an inlet-port A⁶, communicating with the upper interior part of the cylinder. Adjacent the lower end of the cylinder A and on the same side as the former-mentioned valve-casing is arranged a valve-casing A⁸, which communicates with the interior of the cylinder through the inlet-port A⁷, with the casing A⁸ through a passage A⁹, with an exhaust-port A¹⁰ and with the 85 cylinder B through means to be described hereinafter.

Valve-casing B³ is arranged adjacent the upper end of the cylinder B and a casing B⁶ adjacent the lower end of said cylinder. A 90 passage B¹¹ connects the valve-casings A⁸ and B³, and a passage B⁸ is a continuation of the passage B¹¹ and leads to the valve-casing B⁶. The casing B⁶ has communication with the interior of the cylinder B by means of an inlet-port B⁴ and with an exhaust-port, to which is attached a vacuum-pump, by the passage B¹⁰. The casing B⁶ communicates with the interior 95

of the cylinder B through a passage B⁵ and also communicates with an exhaust-passage B⁷, which is also connected to the vacuum-pump.

5 A passage B⁹ leads from the juncture of the passages B⁸ and B¹¹ to the valve-casing C³, from which a port C' leads into the cylinder C. Adjacent the opposite or lower end of the cylinder C is a valve-casing C⁶, having communication with the interior of the cylinder through the passage C⁶, communication with the exhaust and vacuum pump through C⁷, and with the valve-casing C⁸ by means of the passage C⁸. Having now mentioned in detail all the valve-casings and their connecting passage-ways, I will state that a two-way valve D is arranged in the valve-casing A³ and a cut-off valve E in the casing A⁴. Valves similar in construction to the valve E are arranged in the other casings: the valve F in the casing A⁸, G in the casing B³, H in the casing B⁶, I in the casing C³, and K in the casing C⁶.

The operation of my engine is as follows: 25 When the engine starts, the valves are assumed to be in the position shown in Fig. 2, and it will also be remembered that the exhaust-passages are connected to a vacuum-pump and that there is a vacuum below the pistons A' and B' and above the piston C'. Live steam is admitted through the inlet-port A² by way of the casing A³ A⁴ and port A⁶, and the pistons on the rod B² commence traveling in the direction of the arrows in Fig. 2. When about one-fourth 35 of the stroke has been made, steam is cut off, and the steam works expansively during the remainder of the stroke. At the end of the stroke the valves are shifted to the position shown in Fig. 2. It will be borne in mind 40 that up to this time there has been no steam in cylinders B and C. With the shifting of the valves steam passes from the cylinder A, from above the piston A', through passages A⁶ A⁹ B¹¹ B⁸, through the valve-casing B⁶ and port B⁵ to the under side of the piston B' and also through the passage B⁹ to the valve-casing C³, and thence to the upper part 45 of the cylinder C through the port C⁴. The pistons B' and C' therefore commence to move in opposite directions, and it will be remembered that on this movement the piston B' has steam below it and a vacuum above and that the opposite is true of the piston C'. The piston A', however, also originally had a 55 vacuum below it, and in order to destroy this and to more easily enable the pistons B' and C' to force the piston A' back to its original position the passages and valves are so arranged that when the valves are shifted to the 60 position shown in Fig. 3 there will be communication through the valve-casing A³ and port A⁷ between the passage A⁹ and the lower part of the cylinder A. The course of the steam has now been traced, and it has been 65 noted that the steam expands first above the

piston A', second below the piston B', and at the same time a portion of the steam above the piston C'. On the return of the pistons to their original position and the shifting of the valves to the position shown in Fig. 2 70 steam is again admitted through the inlet-pipe A² and, as at first, into the upper part of the cylinder A. The casing A³ is now in communication with the exhaust and the vacuum-pump, and the same is true of the casing B⁶, 75 so that no steam will remain below the pistons A' and B' to cushion them on this second downward stroke. All of the steam which had been admitted to the cylinder A on the first downward stroke has not, however, been exhausted, for as the valves shift to their original position a passage-way is formed through the passages C⁴, casing C³, passage B⁹, casing B⁶, and port B⁴ to the upper part of the cylinder B, which on the previous downward stroke 80 had no steam in it, and also through the passage C⁸, casing C⁶, and port C⁵, establishing a balance on the two sides of the piston C', as had been previously formed in the cylinder A. It will be noted, therefore, that on the second 85 stroke while live steam is working against the upper side of the piston A' and a balance is being formed and maintained in the cylinder C what may be termed "original" steam is working in the upper portion of the cylinder B and is finally exhausted through the passage B¹⁰ at the end of the second downward stroke of the pistons A' and B'. 90

The engine has now been fairly started, steam having been admitted on each side of 100 each cylinder, and it is thought that the further operation of the engine will be clearly understood.

It will be further borne in mind that the aim and object of this construction is to relieve the pistons of any back pressure, which is done in each case at the proper time by either balancing the pressure on each side of a piston or by connecting the exhaust end of the cylinder with a vacuum-pump. At no 105 time during the operation above described is any piston moving against a back pressure.

Having thus fully described my invention, what I claim as new, and desire to secure by Letters Patent, is— 115

1. The combination with a high-pressure cylinder having inlet and exhaust ports, of a low-pressure cylinder arranged in tandem with the high-pressure cylinder, a valve-controlled passage being arranged between the two cylinders, the low-pressure cylinder having an exhaust-port adjacent the end opposite the high-pressure cylinder, a common piston-rod, pistons on said rod, one piston being arranged in each cylinder, a second low-pressure cylinder 120 arranged adjacent the first low-pressure cylinder and having an exhaust-port adjacent one end and a valve-controlled inlet-port adjacent the opposite end in communication with the passage between the two first-mentioned 125 130

cylinders, a piston-rod in the second low-pressure cylinder and a piston on said rod.

2. An engine of the kind described comprising three cylinders, two of said cylinders being arranged tandem, and having suitable pistons and piston-rods, a steam-pipe connected to one of said cylinders, a vacuum-pump having connection with each cylinder, valves adapted to admit steam successively through each of the three cylinders from the steam-pipe mentioned, and means for automatically actuating the said valves.

3. A compound engine comprising a high-pressure cylinder and two low-pressure cylinders, a piston-rod common to the high-pressure cylinder and one of the low-pressure cylinders, a piston in each cylinder, a piston and piston-rod in the other low-pressure cylinder, means for creating a vacuum below the piston on the common piston-rod and above the piston in the other low-pressure cylinder, means for admitting live steam to the high-pressure cylinder only, means for cutting the supply of said steam off when a quarter-stroke has been made, and means for passing a portion of said steam successively into and through the two low-pressure cylinders, substantially as and for the purpose described.

4. A compound engine, comprising a high-pressure cylinder, having a steam-inlet, a two-way valve, inlet and exhaust ports and inlet and exhaust cut-off valves, a passage connecting the inlet and exhaust ports, an exhaust-passage leading from the exhaust-port, a secondary cylinder having inlet and exhaust ports, and inlet and cut-off valves adjacent thereto, a passage connecting the inlet and exhaust ports, an exhaust-port leading from the inlet-port and the exhaust-passage leading from the exhaust-port, a passage leading from the exhaust-ports of the secondary cylinder, and a tertiary cylinder having the inlet and exhaust ports, and inlet and cut-off valves arranged adjacent thereto, a passage connecting the inlet and exhaust ports, an exhaust-passage communicating with the exhaust-port, and a passage communicating with the passage leading from the main cylinder to the secondary cylinder, said main and secondary and tertiary cylinders having suction means connected or communicating with its exhaust-passages, as specified.
